(57) **ABSTRACT**

A sound system processor for converting left and right channel signals from an audio source into composite left and right signals and employing a mid-side processor, at least one low and high pass filters, and one or more sum processors, together which create at least two or more composite signals for delivery to speaker drivers to generate a broad sound field from a compact multi-speaker sound system source.

FIG. 6A

BROAD SOUND LOUDSPEAKER SYSTEM

BACKGROUND

The embodiments herein relate generally to audio speaker systems and, in particular, systems for processing signals from an audio source and directing those processed signals to a plurality of loudspeakers to reproduce high quality stereophonic sound.

By way of background, loudspeakers include electromechanical transducers that convert electrical signals into sound. Audio sources (e.g., stereo systems) typically generate stereophonic sound in the form of separate signals reflecting a left channel (L) and a right channel (R) that are used by electrically connected loudspeakers to generate sounds associated with the left and right channels. To reproduce stereophonic sound in a pleasing manner to listeners within the ambient of the audio source and loudspeakers, a conventional stereo system is typically placed such that at least one loudspeaker reproducing left channel sound is positioned to the left of the listener, while at least one other loudspeaker reproducing right channel sound is positioned to the right of the listener. Other loudspeakers may be employed with audio sources, such as center speakers that combine left and right channel signals or have a dedicated center channel signal, additional left and right channel loudspeakers positioned as a pair in a forward and a rearward position, and a subwoofer to which low frequency signals are parsed from the audio source and reproduced by the subwoofer to present the low bass sounds for the listener.

In many environments, the proper placement of loudspeakers can be difficult to achieve because the sounds reproduced by the plurality of speakers cross paths and, indeed, often interfere with each other. For example, in a portable electronic device, the left loudspeaker and the right loudspeaker may be placed so close together that the resulting stereo separation is inadequate. In another example with separate left and right loudspeakers, space on a countertop or a desktop may be too limited for relatively good placement of the loudspeakers, and in both examples best fidelity is achieved at only one listening position, usually directly in front of and centered between the left and right loudspeakers. In addition, many people do not possess the expertise necessary to position separate loudspeakers for relatively good sound field reproduction.

Many surround-sound systems reflect expertise in loudspeaker layout to minimize interference and maximize robust quality of sound. One desirable result is the reduction in the discernable detection of the point source of sound reproduction; i.e., detection from where the sound is specifically coming. There is a desire among audiophiles to present stereophonic sound reproduced seamlessly throughout the environment, while still detecting the high, medium and low frequency qualities of the sound output.

One problem faced by system designers is providing broad and robust sound where the speakers are presented in a compact, single-body environment, such as a sound bar. The close proximity of the speakers tends to present narrower sound fields, which come across as less robust, and less distinguishable vis-à-vis the variety of frequencies in audio. In other words, less sound separation is achieved. Indeed, the inventor of the present embodiments herein described efforts at addressing this particular problem, presenting meaningful embodiments in U.S. Pat. No. 8,175,304 to North, the contents of which are incorporated herein by reference. Indeed, reference is made to FIG. 1 of this patent, which excerpts FIG. 4 from the '304 patent. Embodiments of the present invention

herein also address at least some of the difficulties in satisfying the desire for broad field sound emanating from compact speaker environments.

SUMMARY

One of several possible sound system processors are provided that are configured to enhance the quality of sound produced by reducing the perception of point-source sound generation. The invention comprises methods of processing signals to generate such broad field sound. The invention also comprises processor embodiments to generate broad field sound. In many embodiments, the processor combines a mid-side processor with low and high pass filters, combining mid and side signals to generate composite signals for use by speaker drivers.

In one embodiment, the sound system processor comprises a mid-side processor configured to process the left signal and right signal inputs and convert them to at least two outputs, 10 one comprising a mid signal L+R output, and the other comprising a side signal L-R output; the sound system configured to split the mid signal L+R output for directing each to different locations; a low pass filter configured to take the other of the split mid signal L+R output from the mid-side processor and remove frequencies above about 100-800 Hz, and preferably above about 300 Hz, from the L+R mid signal to generate a low pass L+R signal output; the sound system configured to split the low pass L+R signal output for directing each to different locations; a high pass filter configured to 15 take the side signal L-R output from the mid-side processor and remove frequencies below about 100-800 Hz, and preferably below about 300 Hz, to generate a high pass L-R signal output; a left channel processor configured to take one of the low pass L+R signal output and the high pass L-R signal output from the high pass filter to generate a composite left channel signal; and a right channel processor configured to take another of the low pass L+R signal output from the low pass filter and a high pass R-L signal to generate a composite right channel signal for delivery to a third speaker driver.

20 In some embodiments, the sound system processor may be configured to split the high pass L-R signal output from the high pass filter into a first high pass L-R signal and a second high pass L-R signal, where the system is configured to deliver the first high pass L-R signal to the left channel processor as the high pass L-R signal input to the left channel processor, the sound system further comprising an inverter configured to take the second high pass L-R signal and invert it to generate the high pass R-L signal output that can be directed to the right channel processor.

25 In other embodiments, the sound system processor may be configured such that the mid-side processor is configured to generate a third output signal comprising a side R-L signal and a second high pass filter configured to take the side R-L signal from the mid-side processor and remove frequencies below about 100-800 Hz, and preferably below about 300 Hz, to generate a high pass R-L signal output that can be directed to the right channel processor.

30 In an alternative embodiment, the processor comprises a mid-side processor configured to process (a) a first of two left channel signals split from an incoming left channel input signal and (b) a first of two right channel signals split from an incoming right channel input signal, wherein the mid-side processor is configured to convert the dual inputs to at least one mid signal L+R output and one side signal L-R output, 35 wherein the at least one mid signal L+R output may be directed to a center speaker driver; a first low pass filter configured to take the second of the two left channel signals

split from the incoming left channel input signal and remove frequencies above about 100-800 Hz, and preferably above about 300 Hz, to generate a low pass left signal output; a second low pass filter configured to take the second of the two right channel signals split from the incoming right channel input signal and remove frequencies of about 300 Hz and greater to generate a low pass right signal output; a high pass filter configured to take the side signal L-R output from the mid-side processor and remove frequencies below about 100-800 Hz, and preferably below about 300 Hz, to generate a high pass L-R signal output; processor configured to split the high pass L-R signal output from the high pass filter into a first and second high pass L-R signal; a first sum processor configured to convert both the low pass left signal from the first low pass filter and the first of the two high pass L-R signals split from the output of the high pass filter into a composite left signal that may be directed to a left speaker driver; an inverter configured to invert the second of the two high pass L-R signals split from the output of the high pass filter; and a second sum processor configured to convert both the low pass right signal from the second low pass filter and the output of the inverter into a composite right signal that may be directed to a right speaker driver.

In some embodiments, surround sound speaker systems are provided that comprising one or more of the sound system processors discussed above, where the speaker systems comprise a plurality of speakers each comprising a speaker driver configured to receive the speaker driver signals output from the processor systems. It is contemplated that at least some of the surround sound speaker systems comprises three speakers positioned to operate in a common rear air chamber. If desired, a passive radiator may be added to embodiments of the speaker systems.

BRIEF DESCRIPTION OF THE FIGURES

The detailed description of some embodiments of the invention will be made below with reference to the accompanying figures, wherein like numerals represent corresponding parts of the figures.

FIG. 1 shows a schematic circuit diagram of one example of a prior art speaker system;

FIGS. 2A and 2B shows a schematic perspective view of one example of a compact speaker system, such as a sound bar;

FIG. 3 shows a schematic circuit diagram of one embodiment of the present invention useful in speaker systems, including compact speaker systems;

FIG. 4 shows a schematic circuit diagram of an alternative embodiment of the present invention useful in speaker systems, including compact speaker systems;

FIG. 5 shows a schematic circuit diagram of yet another embodiment of the present invention useful in speaker systems, including compact speaker systems;

FIGS. 6A and 6B show a schematic perspective view of another example of a compact speaker system.

DETAILED DESCRIPTION OF CERTAIN EMBODIMENTS

By way of example, and referring to FIG. 2A, one example of a generic compact speaker system is shown for context of one application of the embodiments of the present inventive systems. In that regard, a compact speaker system SB comprises a housing for incorporating a plurality of speakers. In this one example of a compact speaker system, which may be in the configuration of a sound bar that could be used as a

stand alone system or incorporated into a larger housing associated with audio systems, furniture, walls, etc., the compact speaker embodiment SB comprises a LEFT speaker, a CENTER speaker, and a RIGHT speaker, each positioned on a front-facing wall and each associated with their own respective speaker drivers. Combinations of drivers may be employed in co-axial or tri-axial speakers for use in the speaker system, if so desired. Indeed, numerous possible arrangements of speakers may be employed in a compact environment, including the incorporation of various types of speakers, such as tweeters, mid-range speakers, sub-woofers, and passive radiators. The embodiment of FIGS. 6A and 6B reflects another example of a compact speaker box SB, which comprises a LEFT speaker, a CENTER speaker, and a RIGHT speaker, each on separate LEFT, CENTER and RIGHT facing walls, respectively. As discussed below, a passive radiator may be positioned on the rear-facing wall in place of a rear speaker with associated rear speaker driver.

In the example shown in FIG. 2B, a specific speaker system embodiment 50 receives a left channel signal AC-L and a right channel signal AC-R from audio source AS. The audio source, of course, may be one of numerous analog and digital systems configured to generate audio signals, whether alone or in combination with video signals. Within the speaker system 50, a processing system 10 may be incorporated to process the left and right channel signals from the audio source to generate pleasing robust sound from the speakers. As an example of one embodiment of a processing system 10, reference is made to FIG. 3, where a dotted line is drawn around the components of the processing system, which receives left and right channel signals AC-L and AC-R from audio source AS to generate signals sent to speaker drivers 52L, 52C and 52R. The components illustrated in FIG. 2B correspond to components identified more specifically in association with FIG. 3.

In that regard, in the embodiment of FIG. 3, by example, the processing system 10 may comprise a mid-side processor 12 configured to receive both the left and right channel input signals from the audio source AS. The output of mid-side processor 12 may comprise a mid signal 14 reflecting the sum of the left and right channel frequencies to generate an L+R signal, that may itself be split into two pathways, 14a and 14b. The output of mid-side processor 12 may also comprise a side signal 16 reflecting the subtraction of right signal frequencies from left signal frequencies to generate an L-R signal. By example only, one of the two pathways of L+R signal 14a may reflect a broadband signal sent directly to a speaker driver, preferably the center speaker driver 52C. Although schematically its position is shown at the top, the center speaker driver 52C may be associated with a speaker placed anywhere within the speaker system, although preferably in a central position vis-à-vis the left and right speakers.

The second pathway of L+R signal 14b is preferably directed through a low pass filter 18, such as a first-order-type filter, to eliminate signals of a certain frequency and above. In one embodiment, the low pass filter is configured to eliminate frequencies above about 100-800 Hz, and preferably above about 300 Hz, to generate a low pass L+R signal 24 that may be split into a first and second pathway 24a, 24b for additional processing. Of course, it is contemplated that the lower level frequency setting may be higher or lower than 300 Hz specifically within that range, depending upon how large the system is. In parallel, the L-R side signal 16 generated by the M-S processor 12 is preferably directed through a high pass filter 20 configured to eliminate frequencies of less than a pre-determined level. In the embodiment shown, the high pass filter 20 is configured specifically to eliminate frequen-

cies below about 100-800 Hz, and preferably below about 300 Hz, although the pre-determined level may be different from within the range of 100-800 Hz, as explained above.

In this example embodiment, the output of high pass filter 20 may be a high pass L-R signal 26, which may be split into a first pathway 26a and a second pathway 26b. Preferably, the first pathway of high pass L-R signal 26a is joined by first pathway of low pass L+R signal 24a as dual inputs to processor 32 for conversion into a single composite signal. In some embodiments, processor 32 functions as a sum processor. In parallel, the second pathway of high pass L-R signal 26b is directed into an inverter to generate an inverted high pass R-L signal 28. This inverted high pass R-L signal 28 is preferably joined with the second pathway of low pass L+R signal 24b as dual inputs to processor 34, which is also preferably a sum processor for conversion of the dual input signals into a composite signal.

Processors 32 and 34 are configured to function as a summing circuit serving to convert two signals into one by adding the two signals together in order to generate a composite left signal 38 and a composite right signal 40. It is contemplated that the composite left signal 38 would be directed to left speaker driver 52L, while the composite right signal 40 would be directed to right speaker driver 52R. As explained above, each speaker driver may be associated with its own speaker, as for example speakers 54R, 54C and 54L associated with speaker drivers 52R, 52C and 52L, respectively, or combined together in one configuration or another. In any case, with such an arrangement as schematically reflected by example in FIG. 3, a broad sound field may be perceived by a listener even though the sound is being generated by closely-positioned speakers. Of course, a robust and broad sound field would be perceived where the speakers are positioned further apart than the compact example of FIG. 2B. It is simply noted that the arrangements and embodiments herein have particular benefit for compact speaker environments.

Other embodiments of left and right audio signal processors are contemplated. For example, with reference to FIG. 4, a processing system 110 may comprise a similar array of components as those reflected in FIG. 3 with some variation. In one example of a variation, a mid-side processor 112 generates three outputs rather than two, as with embodiment 10. In this embodiment, the three outputs reflect a mid L+R signal 114, split into first and second pathways 114a and 114b, as well as a side L-R signal 116a and a side R-L signal 116b. As with mid-signal 14, first and second pathways 114a and 114b are directed to a center speaker driver 52C (associated with speaker 54C) and a low pass filter 118, respectively. In this embodiment, however, the side L-R signal 116a and a side R-L signal 116b each, respectively, pass through parallel high pass filters 120a, 120b. The level of frequencies eliminated (above and below) by the low pass and high pass filters, 118, 120a, 120b, may be set of one of numerous possible levels, although in one embodiment, that level is preferably 300 Hz.

The output of low pass filter 118 is a low pass L+R signal 124 that is split into a first and second pathway 124a, 124b. The output of high pass filter 120a is a high pass L-R signal 126, while the output of high pass filter 120b is a high pass R-L signal 128. The first low pass L+R signal 124a is combined with the high pass L-R signal 126 as dual inputs to processor 132 for converting into a single composite signal, where the processor 132 is preferably a sum processor. Similarly, the second low pass L+R signal 124b is combined with the high pass R-L signal 128 as dual inputs to processor 134, which in some embodiments is a sum processor for converting two signals into a single composite signal. The filters are

preferably configured as described above, but may be configured as necessary to achieve the desired functionality. Both processors 132 and 134 are configured to function as a summing circuit serving to add the two signals together in order to generate a composite left signal 138 and a composite right signal 140, directed to a left speaker driver 52L and a right speaker driver 52R, respectively. As alluded to above, in one example, each speaker driver 52L and 52R is associated with its own speaker 54L and 54R, respectively.

In yet another embodiment of signal processor 210, shown by example in FIG. 5, the left and right channel signals are split so that each has one pathway directed into a low pass filter 212, 218, while the other pathways are joined as dual inputs to mid-side processor 216. The output of low pass filter 212 is a low pass left signal 214, while the output of low pass filter 218 is a low pass right signal 220. The output of the mid-side processor 216 is two-fold: a mid L+R signal 216a and a side L-R signal 216b. The mid L+R signal 216a is directed to a center speaker driver 52C, in a manner as discussed above. Meanwhile the side L-R signal passes through a high pass filter 224 of desired frequency filter, about 100-800 Hz, and preferably about 300 Hz, to generate a high pass L-R signal 226, which is split into a first and second pathway 226a, 226b. The low pass left signal 214 is joined with the first high pass L-R signal 226a as dual inputs to sum processor 230 to generate a composite left signal 232 directed to a left speaker driver 52L. The second high pass L-R signal 226b is passed through inverter 234 to generate a high pass R-L signal and joined with the low pass right signal 220 as dual inputs to sum processor 236 to generate a composite right signal 240 directed to a right speaker driver 52R.

Referring to FIGS. 6A and 6B, such an arrangement of speakers is particularly useful for the examples of processor embodiments of FIGS. 3 and 4. Indeed, with the examples of processor embodiments of FIGS. 3 and 4, bass sound may be generated by employment of a passive radiator on the rear-facing wall, without need of a rear speaker driver. In contrast, the arrangement of front-facing speakers of FIGS. 2A and 2B is particularly useful for the example of processor embodiment of FIG. 5.

Embodiments of the inventive system herein provide several benefits, at least one of which is to process the incoming left/right signal and produce a spacious sound field while also satisfactorily reproducing the bass frequency range without the requirement for separate woofers. In some prior art systems, including the '304 to North identified above, while the benefit is disclosed for using smaller speakers spaced closely together to improve integration of wave fronts and produce a robust sound field, at least one drawback is the need for a separate, dedicated woofer. Embodiments of the present invention eliminate this drawback, permitting a smaller speaker housing, with the system configured to operate at least three speakers in unison to reproduce the bass frequencies while providing a spacious sound field above 300 Hz, or another frequency within the range of about 100-800 Hz. It reflects the science and art of balancing technical requirements (small size, strong bass, and spacious sound). It is further contemplated that embodiments of the present invention may include one or more passive radiators to enhance the sound emanating from a physically small sound field, where the passive radiators may be positioned on the front face of the speaker system, and/or the side, top and rear surfaces as well.

Persons of ordinary skill in the art may appreciate that numerous design configurations may be possible to enjoy the functional benefits of the inventive systems. Thus, given the wide variety of configurations and arrangements of embodiments of the present invention the scope of the invention is

reflected by the breadth of the claims below rather than narrowed by the embodiments described above.

What is claimed is:

1. A sound system processor configured to enhance the quality of sound produced by reducing the perception of point-source sound generation, the sound system processor configured to process a left (L) channel signal and a right (R) channel signal generated by an audio source to generate output, the sound system processor comprising:

a mid-side processor configured to convert the left and right channel signals into three output signals, one output signal comprising an L+R output signal, another output signal comprising an L-R output signal, and yet another output signal comprising an R-L output signal, the sound system configured to split the L+R output signal into a first split L+R output signal and a second split L+R output signal, the first split L+R output signal being deliverable to a first speaker driver when generated;

a low pass filter configured to take the second split L+R output signal from the mid-side processor and remove frequencies of about 100-800 Hz and greater from the second split L+R output signal to generate a low pass L+R output signal; the sound system configured to split the low pass L+R output signal into a first split low pass L+R output signal and a second split low pass L+R output signal;

a first high pass filter configured to take the L-R output signal from the mid-side processor and remove frequencies less than 100-800 Hz to generate a high pass L-R output signal;

a second high pass filter configured to take the R-L output signal from the mid-side processor and remove frequencies less than 100-800 Hz to generate a high pass R-L output signal;

a first sum processor configured to take the first split low pass L+R output signal and the high pass L-R output signal from the first high pass filter to generate a composite left channel output signal deliverable to a second speaker driver when generated;

a second sum processor configured to take the second split low pass L+R output signal from the low pass filter and the high pass R-L output signal from the second high pass filter to generate a composite right channel output signal deliverable to a third speaker driver when generated.

2. A surround sound speaker system comprising the sound system processor of claim 1, further comprising a plurality of speakers, a first speaker comprising a driver for receiving one of the split L+R output signals from the mid-side processor, a second speaker comprising a driver for receiving the composite left channel output signal from the first sum processor, and a third speaker comprising a driver for receiving the composite right channel output signal from the second sum processor.

3. The surround sound speaker system of claim 2, wherein the plurality of speakers are positioned to operate in a common rear air chamber.

4. The surround sound speaker system of claim 2, wherein the plurality of speakers are positioned on separate walls of a speaker box.

5. The surround sound speaker system of claim 4, further comprising a passive radiator.

6. A sound system processor configured to enhance the quality of sound produced by reducing the perception of point-source sound generation, the sound system processor configured to process a left (L) channel signal and a right (R)

channel signal[s] generated by an audio source to generate output, the sound system processor comprising:

a mid-side processor configured to process (a) a first split left channel input signal and (b) a first split right channel input signal into an L+R output signal and an L-R output signal, wherein the L+R output signal is deliverable to a center speaker driver;

a first low pass filter configured to take a second split left channel input signal and remove frequencies of about 100-800 Hz and greater to generate a low pass left output signal;

a second low pass filter configured to take a second split right channel input signal and remove frequencies of about 100-800 Hz and greater to generate a low pass right output signal;

a high pass filter configured to take the L-R output signal from the mid-side processor and remove frequencies less than about 100-800 Hz to generate a high pass L-R output signal; the sound system processor configured to split the high pass L-R output signal from the high pass filter into a first split high pass L-R output signal and a second split high pass L-R output signal;

a first sum processor configured to convert both the low pass left output signal from the first low pass filter and first split high pass L-R output signal into a composite left output signal deliverable to a left speaker driver when generated;

an inverter configured to invert the second split high pass L-R output signal into a high pass R-L output signal; and

a second sum processor configured to convert both the low pass right output signal from the second low pass filter and the high pass R-L output signal from the inverter into a composite right output signal deliverable to a right speaker driver when generated.

7. A surround sound speaker system comprising the sound system processor of claim 6, further comprising a plurality of speakers, a first speaker comprising a driver for receiving the composite left output signal from the first sum processor, a second speaker comprising a driver for receiving the composite right output signal from the second sum processor, and a third speaker comprising a driver for receiving the L+R output signal from the mid-side processor.

8. The surround sound speaker system of claim 7, wherein the plurality of speakers are positioned to operate in a common rear air chamber.

9. The surround sound speaker system of claim 8, wherein the plurality of speakers are positioned on separate walls of a speaker box.

10. The surround sound speaker system of claim 9, further comprising a passive radiator.

11. A method for processing signals generated by an audio source so as to enhance the quality of sound produced by reducing the perception of point-source sound generation, the method applicable to processing a left (L) channel signal and a right (R) channel signal generated by the audio source, the method comprising:

converting the left and right channel signals into three output signals, one comprising an L+R output signal, another comprising an L-R output signal, and yet another comprising an R-L output signal;

splitting the L+R output signal into a first split L+R output signal and a second split L+R output signal,

directing the first split L+R output signal so that it may be received by a center speaker driver;

filtering the second split L+R output signal to remove frequencies of about 100-800 Hz and greater so as to generate a low pass L+R output signal;
 splitting the low pass L+R signal output into a first split low pass L+R output signal and second split low pass L+R signal output;
 filtering the L-R output signal to remove frequencies less than about 100-800 Hz so as to generate a high pass L-R output signal;
 filtering the R-L output signal to remove frequencies less than about 100-800 Hz so as to generate a high pass R-L output signal;
 combining the first split low pass L+R output signal and the high pass L-R output signal into a composite left channel output signal;
 directing the composite left channel output signal so that it may be received by a left speaker driver;
 combining the second split low pass L+R output signal and the high pass R-L output signal into a composite right channel output signal; and
 directing the composite right channel output signal so that it may be received by a right speaker driver.

12. A method for processing signals generated by an audio source so as configured to enhance the quality of sound produced by reducing the perception of point-source sound generation, the method applicable to processing a left (L) channel signal and a right (R) channel signal generated by the audio source, the method comprising:

splitting the left channel signal into a first split left channel input signal and second split left channel input signal;
 splitting the right channel signal into a first split right channel input signal and a second right channel input signal;

5

10

filtering the first split left channel input signal to remove frequencies of about 100-800 Hz and greater so as to generate a low pass left output signal;
 filtering the first split right channel input signal to remove frequencies of about 100-800 Hz and greater so as to generate a low pass right output signal;
 converting the second split left channel input signal and the second split right channel input signals into at least an L+R output signal and an L-R output signal;
 directing the L+R output signal so that it may be received by a center speaker driver;
 filtering the L-R output signal to remove frequencies less than about 100-800 Hz so as to generate a high pass L-R output signal;
 splitting the high pass L-R output signal into a first split high pass L-R output signal and second split high pass L-R output signal;
 combining the low pass left output signal and the first high pass L-R output signal into a composite left channel output signal;
 directing the composite left channel output signal so that it may be received by a left speaker driver;
 inverting the second split high pass L-R output signal into a high pass R-L output signal;
 combining the low pass right output signal and the high pass R-L output signal into a composite right channel output signal; and
 directing the composite right channel output signal so that it may be received by a right speaker driver.
